Carpets

DESIGN.

H. HUNT.

CARPET.

No. 15,993.

Patented Mar. 24, 1885.

UNITED STATES PATENT OFFICE.

HENRY HUNT, OF GREENVILLE, NEW JERSEY, ASSIGNEE TO THE HARTFORD CARPET COMPANY, OF HARTFORD, CONNECTICUT.

DESIGN FOR A CARPET.

SPECIFICATION forming part of Design No. 15,993, dated March 24, 1885.

Application filed January 14, 1885. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surface such as carpets or similar fabrics; and it consists in the novel configuration and grouping of figures herein specifically shown and claimed.

The accompanying photograph is a face view of a carpet showing my new design.

The face of the design is loosely filled with leaf and blossom clusters, (shown dark in the photograph,) which are connected by mossy stems, also shown dark. Occupying the spaces between these groups is a ground of fern sprays and clusters of checkered leaves.

(Shown light in the photograph.) The lichen-like sprays (shown light in the photograph) belong to the ground.

The overlying dark groups are artistically complete in themselves, and in that sense are not interblended with but are independent of the ground.

I claim—

1. The design for a carpet, consisting of the overlying groups and mossy stems, substantially as shown and described.
2. The design for a carpet, consisting of the overlying groups and mossy stems and the fern-spray and checkered-leaf ground, substantially as shown and described.

HENRY HUNT.
